UNITED STATES PATENT OFFICE.

LUCAS PETRON KYRIAKIDES AND RICHARD BLAIR EARLE, OF CAMBRIDGE, MASSACHUSETTS, ASSIGNORS TO HOOD RUBBER COMPANY, A CORPORATION OF MASSACHUSETTS.

PROCESS FOR PRODUCING 1,3-DIOLS.

1,094,224.

Specification of Letters Patent. Patented Apr. 21, 1914.

No Drawing.

Application filed December 21, 1912. Serial No. 738,104.

To all whom it may concern:

Be it known that we, LUCAS P. KYRIAKIDES and RICHARD B. EARLE, citizens of the United States, residing at Cambridge, Massachusetts, have invented certain new and useful Improvements in Processes for Producing 1,3-Diols, of which the following is a specification.

Our invention relates to new processes for producing 1,3-dihydroxyl bodies by the electrolytic reduction of ketone-alcohols. The ketone alcohols are conveniently prepared by the condensation of ketones with formaldehyde by means of alkaline reagents.

Our electrolytic reduction is carried out in acid medium, using lead, nickel, etc., cathodes. The reaction proceeds according to the following equation:

where R stands for a hydrogen atom or an organic radical.

In order to illustrate the new process more fully the following example is given: The electrolytic apparatus consists of the usual anode and cathode compartments. The anode liquid is a dilute sulfuric acid solution, preferably a 10% solution. The cathode liquid consists of a 10% ketone-alcohol solution containing enough sulfuric acid to bring the acid concentration to about 10% of the total solution. The anode consists of an

unattackable material or sheet lead. The cathode is made of clean sheet lead or better 35 a hollow lead spiral, through which water is kept running. The liquids in both chambers are kept at about 15° C., the cathode liquid being stirred during electrolysis. The solution is electrolyzed at a potential 40 difference of about 5-6 volts, and a current density of about 4-5 amperes per 100 square centimeters. There is an excess current passed through the cell to insure complete reduction. The cathode liquid is neutralized 45 with sodium carbonate, the water evaporated off *in vacuo* at as low a temperature as possible, and the glycol is fractionated *in vacuo*. In this way the dihydroxyl body is obtained in more than 50% yield of the 50 theoretical.

We claim:

1. The process for producing 1,3-diols by the electrolytic reduction of ketone-alcohols in acid media. 55

2. The process for producing 1,3-diols by the electrolytic reduction of ketone-alcohols in dilute sulfuric acid solution using lead electrodes.

In testimony whereof, we affix our signatures in presence of two witnesses.

LUCAS PETRON KYRIAKIDES.
RICHARD BLAIR EARLE.
